United States Patent Office

Des. 185,400
Patented June 2, 1959

185,400

TOY CULVERT LOADER

Kenneth Van Dyck, Westport, Conn., assignor to The Lionel Corporation, New York, N.Y., a corporation of New York

Application September 13, 1957, Serial No. 47,732

Term of patent 14 years

(Cl. D34—15)

Fig. 1 is a perspective view of a top culvert loader, showing my new design;

Fig. 2 is a front elevational view;

Fig. 3 is a rear elevational view; and

Fig. 4 is an end elevational view thereof.

I claim:

The ornamental design for a toy culvert loader, as shown.
